(57) **CLAIM**

The ornamental design for a shoelace buckle, as shown and described.

DESCRIPTION

FIG. 1 is a front perspective view of a shoelace buckle showing my new design;

FIG. 2 is a rear perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view of the shoelace buckle of FIGS. 1-6, with the band removed from the buckle for clarity of disclosure; and,

FIG. 8 is a bottom plan view of the shoelace buckle of FIGS. 1-6, with the band removed from the buckle for clarity of disclosure.
